UNITED STATES PATENT OFFICE.

GEORGE W. ROBERTS, OF VANCOUVER, BRITISH COLUMBIA, CANADA.

AUTOMATICALLY-DISCHARGING RAFT.

Application filed August 30, 1926, Serial No. 132,533, and in Canada June 30, 1926.

This invention relates to towing rafts for the transportation of large quantities of logs, cedar bolts and other varieties of timber, and more specifically to that type of raft which is capable of automatically discharging its load.

Its principal object is to provide a raft capable of holding a large cargo of timber but which shall avoid the very considerable expense of unloading the same which has hitherto obtained, and in the process of unloading or discharging log rafts, which are frequently held together by expensive cables, it is frequently necessary to destroy the latter in order to quickly release the cargo.

This difficulty is entirely eliminated by the construction which I adopt.

In addition to the time and labour saving qualities which I secure, a further object has been the production of a raft which is exceedingly compact in form and dimensions as compared with the volume of load conveyed, and consequent upon this there follow the advantages which accrue from its greater handiness and navigational control, also its freedom from the obstructions to navigation which usually characterize unwieldy rafts as frequently constructed.

In securing these objects in view I adopt a construction which consists of a dual framework of squared spars suitably braced together, the whole construction being divided longitudinally into two parts, which, although slightly interlocking, are readily separable into two distinct portions.

These two portions are so constructed as to have the tendency to separate immediately the locking device is released, this action precipitating the whole of the cargo into the water released and ready for disposal.

The construction and functions of my invention are better understood from the drawings herewith, which form part of this application, and in which Fig. 1 is a plan view of the raft; Fig. 2, a side elevation; Fig. 3, an end elevation; and Fig. 4, a detail of the securing and releasing device.

Taking the drawings in detail Fig. 1 is a plan view of the raft showing the two longitudinal and separable portions interlocked about their longitudinal centre line, the two portions being almost identical.

A rectangular framework composed of longitudinal members 2 secured to transverse members 4 and vertical members 5 and further strengthened by the angular pieces 6

and the diagonals 7 is secured to its fellow and corresponding portion by cables at intervals marked 8.

These latter are securely spliced around the top longitudinal member 9 on one side and passed across but underneath the corresponding member on the opposite half of the raft, terminating in an eyelet which is passed through a stout linked hook bolt depending from one of the verticals and secured thereto and there secured by a movable link.

Transverse members from the floor of the raft project at intervals sufficiently to engage the lower longitudinal spar of the adjacent opposite half of the raft, so that each adjacent portion along the centre impinges and rests upon the other, as shown at 10.

The cargo of logs or the like is then laid upon the combined raft resting upon the cables 8 which are thus made taut and so brace the verticals against the load.

The load is then in a position for transportation, the whole structure being effectively held together by the abuttal of the lower brace of the raft and tensile strength of the cables tightened by the weight of the cargo.

When it is desired to disengage the raft from its load all that is necessary is to drive up the engaging link 11 whereupon the strain imposed on the cable by the weight of the cargo immediately turns over and disengages the link hook 12, rendering each half of the raft separable, the angularity of the bracing spars 6 in conjunction with the weight of the cargo forcing the two longitudinal halves of the raft to float apart and free from the load. Thus the releasing of the load is effected without loss or damage to any of the cables or connections and in the merest fraction of time usually taken.

It is to be noted that it may be necessary to secure the cargo of logs from possible longitudinal movement in a direction opposite to that of the course of the raft.

This can be effected in a number of ways, one method being as indicated in the drawing where at one end of each section a vertical stanchion 13 is shown with a diagonal brace 14 secured thereto.

What I claim as new and desire to be protected in by Letter Patent, is:

1. A rectangular framework of spars, said framework being separable along its longitudinal centre line into two approximately similar portions, each of said portions having

transverse members sloping downwardly from the outside wall to the longitudinal centre, the said outer wall consisting of intersecting vertical and horizontal members, cables at suitable intervals adapted to unite the two said separable portions, said cables secured to top horizontal member of said outer wall of one separable portion, said cables being passed below the corresponding 10 top horizontal member of the other said separable portion, and means adapted to releasably secure the ends of said cable to the said vertical members.

2. A rectangular framework of spars, said 15 framework being separable along its longitudinal centre line into two approximately similar portions, each of said portions having transverse members sloping downwardly from the outside wall to the longitudinal 20 centre, transverse members of said framework projecting beyond the longitudinal centre line of said framework, and adapted to overlap and bear upon the adjacent longitudinal member of the other said separable 25 portion, and thus adapted to retain the two halves of said framework in a common plane.

3. A rectangular framework of spars, said framework being separable along its longitudinal centre line into two approximately 30 similar portions, each of said portions having transverse members sloping downwardly from the outside wall to the longitudinal 35 centre, the said outer wall consisting of intersecting vertical and horizontal members, cables at suitable intervals adapted to unite the two said separable portions, said cables secured to top horizontal member of 40 said outer wall of one separable portion, said cables being passed below the corresponding top horizontal member of the other said 45 separable portion, means adapted to releasably secure the ends of said cable to the said vertical members, said means including a pair of linked eye bars, one of said bars being secured to one of the vertical members of said framework and the other said bar being adapted to pass through an eye placed in the extremity of said cable forming a 50 lever fulcrumed within the eye of the other said bar and secured thereto by a slid able link.

In testimony whereof I affix my signature,
GEORGE W. ROBERTS.
